AUTOMOBILE LICENSE PLATE HOLDER

George A. Gazan, Jr., Ferndale, Mich.

Application April 16, 1949, Serial No. 2,075

Term of patent 14 years

(CL. D14—6)

To all whom it may concern:

Be it known that I, George A. Gazan, Jr., a citizen of the United States, residing at Ferndale, in the county of Oakland and State of Michigan, have invented a new, original, and ornamental Design for an Automobile License Plate Holder, of which the following is a specification, reference being had to the accompanying drawing forming part thereof:

Fig. 1 is a front view of my new automobile license plate holder.

Fig. 2 is a horizontal cross sectional view taken along line 2—2 of Fig. 1.

Fig. 3 is a vertical cross sectional view taken along line 3—3 of Fig. 1, and

Fig. 4 is a vertical cross sectional view taken along line 4—4 of Fig. 1.

Fig. 5 is a vertical cross sectional view taken along line 5—5 of Fig. 1.

The characteristic features of my design are shown by means of full lines in the drawing. The dotted line showing of the letters is for illustrative purposes only.

I claim:

The ornamental design for an automobile license plate holder as shown and described.

GEORGE A. GAZAN, JR.
